UNITED STATES PATENT OFFICE.

CHARLES L. GOODRUM, OF BROOKLYN, NEW YORK, ASSIGNOR TO WESTERN ELECTRIC COMPANY, INCORPORATED, OF NEW YORK, N. Y., A CORPORATION OF NEW YORK.

MACHINE-SWITCHING TELEPHONE SYSTEM.

1,250,579.

Specification of Letters Patent. Patented Dec. 18, 1917.

Application filed October 6, 1916. Serial No. 124,069.

To all whom it may concern:

Be it known that I, CHARLES L. GOODRUM, a citizen of the United States, residing at Brooklyn, in the county of Kings and State 5 of New York, have invented certain new and useful Improvements in Machine-Switching Telephone Systems, of which the following is a full, clear, concise, and exact description.

10 This invention relates to telephone exchange systems employing machine switching.

Its object is to provide a circuit arrangement for systems of this character wherein 15 the calling party may ring the bell of the called party after such party has replaced his receiver upon the switchhook at the termination of the conversation.

In the circuit arrangement of this invention, the connector is provided with a side switch which advances from the ringing to the talking position upon the response of the called party and connects a magnet to a back contact of the stepping relay of the 25 connector. If, when the called party hangs up his receiver, the calling party desires to resignal such party, he operates a switch associated with his substation set, which momentarily deenergizes the connector stepping 30 ping relay to close the circuit of said magnet. The magnet is provided with an armature which, when actuated, resets the side switch from the talking position to the ringing position, whereupon the called line is again automatically signaled, the response of the called party causing the side switch again to advance to the talking position.

Figure 1 is a diagram of a circuit arrangement embodying this invention, and Fig. 2 40 is a side elevation, partly in section, of the modified side switch for use therewith.

The invention will be readily understood from a detailed description of the operation.

Upon the removal of the receiver at substation A, a line finder or similar non-numerical switch is set in motion, and associates the calling line with a connector C, whereupon the stepping relay 1 thereat becomes energized over the calling line circuit, 45 and at its armature and front contact, energizes a slow relay 2. Relay 2, in attracting its left armature, interposes a break in the circuit of release magnet RM, and in attracting its right armature, connects the back 50 contact of relay 1 to the primary stepping 55 contact of relay 1 to the primary stepping

magnet 3 of the connector. The calling party now operates his sender S to transmit the tens series of impulses. Each time the relay 1 retracts its armature, as the sender S in restoring to normal interrupts the line 60 circuit, an impulse is transmitted over the following circuit to magnet 3, to position the connector brushes 4, 5 and 6 in operative relation to the group containing the called line terminals 7, 8 and 9: ground, armature 65 and back contact of relay 1, right armature and front contact of relay 2, conductor 47, connector side-switch arm 44 and its first contact, magnet 3, free pole of battery. Upon the first retraction of the armature of 70 relay 1, a slow relay 43 becomes energized and remains energized as the armature of relay 1 vibrates. This relay 43, in attracting its right armature, energizes the side-switch escape magnet 45 over a circuit including the armature and back contact of ringing cut-off relay RCO. When, however, the sender restores, this relay become deenergized, opening the circuit of the escape magnet which thereupon releases the 75 side switch into position 2. In position 2, the arm 44 substitutes secondary magnet 46 in the stepping circuit for the primary magnet 3.

The calling party now operates his sender 80 S to transmit the units digit of the called line. As before, the slow relay 43 is energized upon the first retraction of the armature of relay 1, and remains energized as the sender is operating. The relay 1, in operating, transmits impulses to the magnet 46 which steps the brushes 4, 5 and 6 over the selected group, and into engagement with multiples 7, 8 and 9 of the called line. When the sender S restores and maintains the relay 90 1 energized, relay 43 becomes deenergized after a slight interval, opening the circuit of the escape magnet 45, which releases the side switch into position 3. In position 3 relay 43 is again energized over the following circuit to energize the escape magnet to apply ringing current to the called line: free pole of battery, relay 43, conductors 10, 47, arm 44 and its third contact, conductors 11, 12, 13 to ground at the armature and front contact of relay 1. The attraction of the right armature of relay 43 energizes the escape magnet 45 which, in attracting its armature, closes the ringing circuit as follows: free pole of battery 15, or ringing generator 16, de- 100 105 110

pending upon the position of the commutator 17, brush 18, relay RCO, armature and front contact of magnet 45, conductor 19, arm 20 and its third contact, brush 5, multiple 8, 5 bell 22 at the substation B, condenser 21, multiple 7, brush 4, arm 23 and its third contact, conductors 12, 13, to ground at the armature and front contact of relay 1. When the party at substation B removes his 10 receiver, relay RCO becomes energized, opening the circuit of the escape magnet which releases the side switch into position 4. In position 4, talking current is fed to the called line over the following circuit: free pole of battery, left winding of relay 24, conductors 25, 26, arm 23 and its fourth contact, brush 4, multiple 7, through the telephonic apparatus at substation B, multiple 8, brush 5, arm 20 and its fourth contact, conductors 27, 15 28, right winding of relay 24 to ground. In position 4 of the side switch, side-switch arm 42 connects magnet 49 to conductor 30 to which is connected a front contact of the slow relay 2, which relay is now energized 20 and consequently the connection of this relay is extended to the back contact of stepping relay 1. It will be noted that the circuit of the release magnet of the connector leads over the left armature and back contact of 25 relay 2, and that therefore the control of the release of the connector is vested in the calling party.

If, now, the called party replaces his receiver, and the calling party desires to 30 signal such party, he operates his sender S to interrupt the line circuit. This results in the energization of magnet 49 over the following circuit: ground, armature and back contact of relay 1, right armature and front contact of relay 2, conductors 30, 31, side-switch arm 42 and its fourth contact, magnet 49 to free pole battery. Magnet 49, in attracting its armature 32, (Fig. 1), moves the arm 48 thereon upwardly, causing such arm 40 to engage side-switch lever 33, the construction and arrangement being such that the attractive movement of the armature 32 is just sufficient to set back the side-switch arms *a* from the fourth set of contacts *c* to the third set, in which position such arms 45 are held by the holding pawl *m*, engaging the tooth *t* of the ratchet *r* of the side-switch escapement.

The resetting of the side switch to the 50 third position causes the closure of the ringing circuit traced, and upon the removal of the receiver at substation B, the relay RCO, in deenergizing the escape magnet, releases the side switch to position 4 to open the ringing circuit. The subscribers again converse, and when the parties replace their receivers, the following circuit is closed for the release 55 magnet RM of the connector: free pole of battery, right winding of magnet RM, right armature and back contact of relay 24, off-

normal contact PON, conductors 34, left armature and back contact of relay 2, conductors 35, 36, left armature and back contact of relay 24, right armature and back contact of relays 2 and 1 to ground. If the calling party replaces his receiver before the called party, the following circuit is closed to release the switches preceding the connector: armature and back contact of relay 1, right armature and front contact of relay 70 2, which, being slow, maintains its armatures attracted for an interval after the armature of relay 1 reaches its back contact, conductors 47, 37, left armature and front contact of relay 24, conductor 36 to the test wire 50, 80 leading to the release magnets of the preceding switches. When the called party replaces his receiver, magnet RM is energized over the following circuit: free pole of battery, right winding of magnet RM, right 85 armature and back contact of relay 24, off-normal contact PON, conductor 34, left armature and back contact of relay 2, conductors 35, 36, left armature and back contact of relay 24, right armatures and back 90 contacts of relays 2 and 1 to ground.

If the called line is busy, the test multiple 9 thereof is grounded, and when the test brush 6 is set thereon, the following circuit is closed for the release magnet RM of the connector: ground, multiple 9, brush 6, arm 38 and its second contact, left armature and back contact of relay 43, conductor 34, contact PON, right armature and back contact of relay 24, right winding of relay RM free pole 100 of battery. The left armature of relay 43 closes its back contact before the circuit of the escape magnet 45, leading over the right armature of said relay, is opened, long enough to cause the deenergization of the escape magnet. 105 Therefore, the circuit traced is closed over side-switch arm 38 and its second contact, before the escape magnet can release the side switch into position 3. The release magnet, in operating, locks itself over the following 110 circuit: free pole of battery, left winding of magnet RM, its armature and front contact, conductors 39, 40, 13, to ground at the armature and front contact of relay 1. Magnet RM, in attracting its right armature, 115 connects a source of busy tone current 41 to the talking conductor 27 and thence to the calling line. When the calling party replaces his receiver, relay 1 becomes deenergized, opening the locking circuit for 120 the magnet RM and releasing the preceding switches, as described. The release magnet RM, in energizing, restores the side-switch arms in the well-known manner.

While only one automatic switch is shown, 125 it will be understood that in practice a connection would lead over a train of selectors to the connector shown.

What is claimed is:

1. In a telephone exchange system, the 130

- combination with telephone lines, automatic switches adapted to interconnect the same including a connector, a side switch for said connector, means operated by the response 5 of the called party for advancing said side switch from the ringing to the talking position, and means controlled by the calling partly for resetting the side switch from the talking directly to the ringing position.
- 10 2. In a telephone exchange system, the combination with telephone lines, automatic switches including a connector, a stepping relay therefor, a sender adapted to interconnect said lines by means of said switches, a 15 side switch for said connector, means for advancing said side switch from the ringing to the talking position upon the response of the called party, and a magnet, means for connecting said magnet in the talking position 20 of the side switch to a contact of the stepping relay, whereby, upon the operation of the sender in the talking position of the side switch, said magnet is arranged to reset the connector from the talking to the ringing 25 position.
3. In a telephone exchange system, the combination with telephone lines, a connec-
- tor, a side switch therefor, senders associated with said lines adapted to set said connector on said lines, means for advancing said side switch from the ringing to the talking position upon the response of the called party, a magnet, said side switch in its talking position connecting said magnet to a back contact of the stepping relay, and an armature carried by said magnet adapted to engage said side switch and reset the same from the talking to the ringing position when said magnet is energized.
4. In a telephone exchange system, the combination with telephone lines, means for interconnecting the same including an automatic switch, a side switch therefor, including a control magnet, means controlled by the calling party for setting said automatic switch on a called line, an auxiliary magnet for said side switch, means for placing the same under control of the calling party when said automatic switch is set, and means controlled by such party for operating said auxiliary magnet to reset said side switch.

In witness whereof, I hereunto subscribe my name this 4th day of October, A. D. 1916.

CHARLES L. GOODRUM.
